E. OHNSTRAND.
FURNITURE DRAWER.
APPLICATION FILED OCT. 28, 1912.

1,222,451.

Patented Apr. 10, 1917.

UNITED STATES PATENT OFFICE.

ENOCH OHNSTRAND, OF SYRACUSE, NEW YORK, ASSIGNOR TO U. S. STEEL FURNITURE COMPANY, OF SYRACUSE, NEW YORK, A CORPORATION OF NEW YORK.

FURNITURE-DRAWER.

1,222,451.

Specification of Letters Patent. Patented Apr. 10, 1917.

Application filed October 28, 1912. Serial No. 728,124.

To all whom it may concern:

Be it known that I, ENOCH OHNSTRAND, of Syracuse, in the county of Onondaga and State of New York, have invented a new and useful Improvement in Furniture-Drawers, which improvement is fully set forth in the following specification and shown in the accompanying drawings.

The present invention relates to furniture drawers and an object of the same is to provide a construction which may be inexpensively formed from sheet metal and in which the parts thereof may be quickly and easily assembled.

15 To these and other ends the invention consists in certain parts and combinations of parts all of which will be hereinafter described, the novel features being pointed out in the appended claims.

20 In the drawings:

Figure 1 is a perspective view of the body of the drawer with the front wall removed;

Fig. 2 is a perspective view of the inner face of the outer section of the front wall;

25 Fig. 3 is a perspective view of one face of the inner section of the front wall;

Fig. 4 is a detail sectional view showing the manner of connecting the front wall to the drawer bottom;

30 Fig. 5 is a longitudinal section of the drawer showing the front wall in position; and

Fig. 6 is a horizontal section through the front wall of the drawer.

35 The drawer body may be of any suitable construction but is preferably formed from a single piece of sheet material bent to provide the bottom wall 1, side walls 2 and 3 and a rear end wall 4, the side walls and

40 rear end walls being bent vertically with reference to the bottom wall 1 and the rear edges of the side walls 2 and 3 being connected to the rear end wall 4. In this instance, this connection embodies laterally

45 turned tongues 5 on the rear ends of the side walls 2 and 3 overlapping the rear face of the end wall 4 and being provided with lips 6 which extend through slits 7 in the rear wall 4, said lips being bent laterally over

50 the inner face of the rear wall. The bottom wall, preferably, is depressed or dropped at 8 longitudinally along its opposite sides to provide portions which coöperate with the

guides on which the drawer slides, thus elevating the intermediate portion of the bot-

tom and reducing the friction on the bottom of the drawer.

The front wall of the drawer is formed preferably of two sections, an outer section 9 and an inner section 10. In this instance, 60 this front section is connected to the drawer body by forming angled flanges on the side and bottom walls of the body, said flanges having portions 11 extending at right angles to the walls by which they are carried and 65 having forwardly deflected flanges 12 at their outer edges parallel with the said walls. On the bottom wall, the angled flange is provided only between the dropped or depressed portions 8. To coöperate with 70 these angled flanges, the front section 9 may be provided on its inner face with a marginal pocket formed by bending the sheet of metal rearwardly at 13 at right angles to the plane of the wall, and thence inwardly 75 at 14 parallel with the plane of the wall, this pocket receiving the angled flanges 11, 12 on the bottom and side walls of the drawer bottom.

The inner section 10 of the front wall may 80 be provided with marginal flanges 15 along its sides and with a marginal flange 16 along its bottom edge, the flanges 15 and 16 being straight or flat and the flanges 15 having their lower ends cut away or beveled to 85 permit the flange 16 to yield slightly when the inner section is being fitted to the front section. At its upper edge, the inner section is provided with an angled flange formed by a portion 17 extending from and 90 arranged at right angles to the plane of the section 10, a portion 18 extending from the portion 17 and parallel with the portion 10, and a portion 19 extending from the outer edge of the portion 18 and parallel with the 95 portion 17. The angled portions 18 and 19 are adapted to be fitted within that portion of the marginal pocket along the upper edge of the outer section 9, as shown in Figs. 4 and 5, so that, when the lower end of the 100 inner section 10 is brought up to the outer section 9, the inner section will abut the inner face of the drawer body and hold the outer section in place.

Arranged on the front face of the front 105 wall is a handle 20 which is preferably secured in place by two bolts. These bolts may have heads 21 and are loosely passed through openings 22 in the inner section, being provided with shoulders 23 which 110

abut the inner face of the outer section 9, screw threaded portions 24 beyond said shoulders 23 engaging in screw threaded openings in the handle 20 so that the outer section is clamped between the shoulders 23 and the handle 20.

- Another important feature of this invention is the manner of mounting the lock, the latter having an attaching plate 25 riveted or otherwise secured to the inner face of the inner section 10 immediately below the inwardly turned portion 17 which has an opening through which the bolt 26 is adapted to be projected. Extending forwardly from the attaching plate is the barrel 27 of the lock, provided with the key opening, said barrel being adapted to project slightly through an opening 28 formed in the front section 9.
- 20 A drawer constructed in accordance with this invention has special advantages for resisting fire. Its front wall is formed of two members or sections which are spaced apart so as not to provide any two wide abutting portions adapted to transmit heat from one section to the other. The angled flanges on the drawer body serve to increase the width between the two members of the front wall, and, at the same time, permit 25 the drawer to simulate a wooden construction having a surrounding projection on its front wall to exclude dust. The lock is only secured to the inner section of the front wall and, in this way, may be more readily assembled while permitting a knock-down construction. The handle is connected to the drawer without tying the two sections or members of the front wall into abutting relation.
- 40 What I claim as my invention and desire to secure by Letters Patent is:

1. In combination in a drawer for furni-

ture, a body having angled flanges on the forward ends of its bottom and side walls, said flanges extending outwardly with reference to said walls and then forwardly; and a front wall embodying an inner and an outer section, the outer section having a marginal pocket formed by portions extending rearwardly and inwardly, said 45 pocket receiving the flanges on the side and bottom walls of the body, and the inner section coöperating with the inner face of the body and having a portion fitted in that portion of the marginal pocket along the 50 upper edge of the front section.

2. In combination in a drawer for furniture, a body having angled flanges on the forward ends of its bottom and side walls, said flanges extending outwardly with reference to said walls and thence forwardly 55 parallel with said walls; and a front wall formed of an inner and an outer section, the outer section having a marginal pocket formed by portions extending rearwardly and inwardly, said pocket receiving the angled flanges on the side and bottom walls 60 of the body, and said inner section having straight flanges on its vertical side and bottom edges and an angled flange along its upper edge, the angled flange extending forwardly at right angles to the plane of the section, thence upwardly parallel with the plane of the section, and thence forwardly 65 at right angles to the plane of the section, the last-named forwardly extending portion and the outwardly extending portion being received within that portion of the marginal pocket along the upper edge of the front section.

ENOCH OHNSTREND.
